METHOD OF MAKING PLASTER-GROUND
FABRIC

Archworth Martin, Pittsburgh, Pa.

Application February 2, 1938, Serial No. 188,283

6 Claims. (Cl. 1-2)

My invention relates to plaster-ground fabric structures comprising plaster reinforcing mesh, to the rear side of which is secured a backing sheet or form sheet, the fabric structure being placed upon studding or other framework with the mesh outwardly and plaster or cement then applied against the same in the forming of walls, floors, ceilings, etc.

For convenience of handling and installation, it has been common practice to assemble the backing sheet and the reinforcement mesh in unitary relation at the factory. The methods heretofore employed in assembling the backing sheet and the mesh have been somewhat expensive, owing to the fact that such operation has been performed either by the manual insertion of wire clips at various spaced points, to tie the backing sheet to the mesh, or by intermittently-operable mechanical means. In the latter case, the backing sheet and the mesh are periodically advanced past a given point, and at each pause lacing wires or the like are threaded through the structure, each wire lying partly in front of the wire mesh and partly behind the paper. Not only are such operations tedious and expensive, but in many instances holes of objectionable size are made in the backing sheet during insertion of the sheet-retaining or tie elements.

One object of my invention is to provide a method whereby reinforcement mesh and backing sheets of any length can be advanced continuously and the sheet attached to the mesh during said advancing movement.

Another object of my invention is to provide a plaster base structure of improved form wherein the backing sheet is attached without the necessity of punching holes therein, or without punching holes of objectionable size.

Still another object of my invention is to provide a plaster base structure wherein the backing sheet is more effectively held in position than in various forms of fabric structures heretofore employed, and wherein a minimum amount of plaster or cement is required in order to produce a completed structure of adequate strength.

Some of the methods by which my invention may be practiced and the forms of fabric structure produced thereby are shown in the accompanying drawings wherein Figure 1 is a longitudinal sectional view showing one manner in which the backing sheet may be connected to the reinforcement mesh by means of a metal retaining strip; Fig. 2 is a longitudinal sectional view on an enlarged scale showing a portion of

fabric structure produced according to the disclosure of Fig. 1; Fig. 3 is a view taken on the line III—III of Fig. 2; Fig. 4 shows still another manner in which a metal retaining strip can be employed for securing the backing sheet to the reinforcement mesh; Fig. 5 is a view taken on the line V—V of Fig. 4; Fig. 6 is a plan view of a portion of the structure of Fig. 4; Fig. 7 is a sectional view of a portion of the completed fabric structure of Fig. 4; Fig. 8 is a side view, partly in section, showing another manner in which the backing sheet may be connected to the reinforcement mesh; Fig. 9 is a perspective view showing a portion of the completed fabric structure formed in the manner disclosed in Fig. 15; Fig. 10 is an enlarged view taken on the line X—X of Fig. 9; Fig. 11 is a view taken on the line XI—XI of Fig. 10; Fig. 12 is a view similar to Fig. 10 but showing a modification of the structure thereof, and which may be assembled in the manner shown in Fig. 8; Fig. 13 is a view taken on the line XIII—XIII of Fig. 12, and Fig. 14 is a view showing still another form of tie strip.

Referring first to Figs. 1, 2 and 3, the reinforcement mesh is shown as consisting of longitudinal wires 15 that are welded to transverse wires 16. Sheet metal ribs 17 are welded to the longitudinal wires 15 and serve not only to stiffen the fabric, but as a means for producing a ribbed plaster structure, as will be hereinafter explained.

A backing sheet 18 of paper or other flexible material, which is approximately co-extensive in width with the wire mesh, is drawn from a supply roll 19 past guide rolls 20 that serve to tension the paper, and between feed rollers 21 and 22 which are driven from any suitable source of power. Additional advancing movement is exerted upon the sheet 18 by soft-faced feed rollers 23 and 24, which also advance the mesh. A suitable number of metal tie strips 25 having tang elements 27 struck out therefrom, are drawn from reels 26, the tangs initially lying close to the strips so as to permit of their being wound upon the reels. The strips may be of light gauge metal. The strips are drawn past a guide roller 28 and past a bending bar 29, the bar 29 having a nose portion of such angularity that the strips are sharply flexed when passing around the same, thus causing the tangs 27 to be projected outwardly from the strips. As the tangs approach the rolls 21—22, they will be pressed through the sheet 18, the roll 22 being provided with peripheral grooves that will permit the tangs to pass without being flattened down. The sheet 18 and

the strips 25 pass over a guide roller 30, and the sheet 18 is thereby brought into engagement with the underside of the mesh.

The tangs, when they reach the plane of the reinforcement mesh, will be projected upwardly through the mesh openings at points adjacent to the transverse wires 16 of said mesh, and as they move past a bar 31 will thereby have their upper ends bent to right-angular position over the transverse wires. Thereafter, they will be engaged by bending dies or arms 32 (one for each strip) that are mounted on a shaft 33. Springs 34 serve to bias the dies 32 in a clockwise direction. When the bent tangs engage the longer arms of the dies 32, they will cause the said arms to be rocked in a counter-clockwise direction, thus causing the shorter legs of the dies to bend the ends of the tangs downwardly around the transverse mesh wires 16. Upon completion of this operation, the tangs thus bent will pass out of engagement with the dies and the dies will be swung by their springs back to the position shown in Fig. 1, ready to be engaged by other tangs. A rigidly-mounted guide or back-up plate 35 is provided for supporting the fabric members against downward deflection under pressure of the bending dies 32. In cases where it is not desired that the plaster body have ribs formed on its rear side, the V-bars 17 will be omitted.

The V-bars 17 not only serve as stiffening and spacing elements, but as reinforcing elements, and a fewer number of transverse wires 16 will be required; or, if a sufficient number of the V-bars are used, the wires 16 may be omitted entirely, in which latter case the tangs 27 will be bent over the V-bars.

In Figs. 4 to 7 I show an arrangement wherein metal tie strips 36 are placed against the face of the mesh 38 and the tangs 37 thereof are pushed through the backing sheet 39 that is located at the rear side of the mesh. In this arrangement the members 36, 38 and 39 are advanced by feed rollers 40, 41, 42 and 43.

The tanged strips 36 are each drawn between a pair of rollers 44 and 45, and they initially have their tangs protruding from the edges thereof in the plane of the strips. Each roller 45 is provided with flanges 46 which extend alongside the ends of each roller 44, in position to engage the tangs 37 and bend them at right angles to the planes of the strips. When the tangs approach the rollers 40 and 41, they are pushed through the backing sheet and pass through circumferential grooves in the roller 41.

Bending dies 47 are provided for bending the tangs behind the sheet 39, to hold the sheet in place. Each die has a rounded or flared nose portion 48 whose sides are engaged by the tangs to guide them, so that the lower extremities of the tangs will be forced into engagement with curved die surfaces 49 that slope upwardly and outwardly in a direction away from the nose portion 48 and bend the tangs upwardly against overhanging ledges 50 carried by the upper part of the die, the bent portions of the tangs passing from under these ledges as the strip is carried past the die. The ledges or flanges 50 prevent tearing of the backing sheet 39 during bending of the tangs. An idle roller 51 holds the strips 36 against springing upwardly when the tangs are being bent. When the tangs have been carried past the rollers 42 and 43 they will be bent upward snugly against the sheet, somewhat as shown in Fig. 7.

In the structures of Figs. 1 to 7, expanded metal mesh may be employed instead of the strand and stay wire mesh 15-16. Also other forms of tie strips may be employed in the structures of Figs. 1 to 7, as for example, the strip shown in Fig. 14 wherein the wires 36a correspond to the tie strip 36 and the prongs 37a correspond to the tangs 37.

Referring now to Figs. 8 to 11, I show another manner in which a backing sheet 52 may be applied to a reinforcing mesh 53. Sheet metal ribs 54 are welded to the longitudinal wires of the mesh or fabric 53. The backing sheet 52 is drawn from a supply roll 55 as the material is advanced. Rolls 56 and 57 are driven from any suitable source of power and are of yieldable material such as soft rubber. Additional driving, soft-faced rolls 58 and 59 also serve to advance the fabric and the paper sheet, all of the rolls being constantly driven. Retaining strips 60 of heavy paper or cloth tape, drawn from supply rolls 61, are also passed between the feed rolls, so that they are drawn along with the mesh and the backing sheet. A suitable number of strips 60 will be provided to adequately hold the backing sheet against the mesh. The strips are coated on the under sides with an adhesive such as one of the water-proof glues well known on the market, the coating being effected by an idling roller 62 that extends into a glue tank 63 and is rotated by travel of the strips.

Adhesive may also be applied to the sheet 52 along lines that will be engaged by the strips 60. The glue thus provided may be in lieu of or in addition to the glue applied to the strips 60. The adhesive material applied to the sheet and the strips may be of the kind applied to the co-acting sealing flaps of "self-sealing" envelopes. Adhesive of this kind can be pre-applied to the strips 60 and along predetermined lines on the backing sheet 52. Also, a cement or glue can be utilized which is soft only at high temperatures. In the latter case, a glue tank 64 will be positioned to discharge through spouts 65 to the backing sheet and a burner 66 or other heating element provided for liquefying the glue. The lines of glue discharged through the spouts 65 will remain soft until engaged by the strips 60. To hasten the cooling of the glue and hence the tenacity thereof, cooling air is supplied through a pipe 67 that extends transversely of the fabric and discharges jets of air through holes formed in its lower portion.

It will be understood that the rolls 56, 57, 58 and 59 in advancing the strips, the mesh and the backing sheet, will press said elements snugly together, and that they, nevertheless, will be of sufficient softness to avoid flattening of the V-bars 54.

It will be seen that the fabric structure thus produced has no holes in its backing sheet, and that by reason of the presence of the V-bars 54, ribs of considerable thickness will be formed on the rear side of the plaster which is applied to the fabric structure, and that the said ribs will add strength to the plaster structure, thus making it possible to apply a thinner coat of plaster at points between the ribs, where the sheet is held in forwardly-deflected position. The V-bars besides spacing the paper from the mesh at those points, also are embedded by the plaster and serve to reinforce the ribs formed thereon. The spacing of the transverse wires over which the strips 60 are laid is such that the strips can conven-

iently be forced snugly into engagement with the sheet 52, throughout most of their areas, thus causing them to lie more smoothly and to have greater holding force than if they were attached to the backing sheet by mere spots of adhesive.

5 In Figs. 12 and 13 I show a structure which may be formed in substantially the same manner as the structure of Figs. 8 to 11. This second form differs from the first form merely in the omission 10 of the V-ribs. It consists of a backing sheet 68 which, as in the case of Fig. 8, may be of paper, or other suitable fibrous material or a sheet of very fine mesh, such as screen cloth. The retaining strips 10 may also be of heavy paper or 15 cloth tape. In any event, the sheet 68, mesh 71 and the tape 10 are fed between rollers in the same manner as shown in Fig. 8.

The flexibility of the tie strips shown in the various figures of the drawings will permit them 20 to yield somewhat under trowel pressure, thus permitting better embedment of the reinforcement mesh in the plaster which is applied to the fabric base.

I claim as my invention:

25 1. The method of making a base for plastic material, which comprises continuously advancing reinforcement mesh and a backing sheet therefor, in superposed relation, simultaneously applying a tanged tie strip to the exposed face 30 of the sheet and pushing the tangs through the sheet, and bending the projecting ends of the tangs against the exposed face of the mesh.

2. The method of making a base for plastic material, which comprises imparting advancing 35 movement to a reinforcement mesh having portions disposed transversely of the path of movement, in conjunction with a backing sheet therefor, simultaneously applying a tanged tie strip to the exposed face of the sheet and pressing the tangs thereof through the sheet at successive 40 points in front of the said transverse portions, bending the tangs backwardly over the said members, and advancing successive portions of the tie strip into assembled relation with the mesh 45 and the sheet through pulling force transmitted from the transverse members to the tangs.

3. The method of making a base for plastic material, which comprises imparting advancing movement to a reinforcement mesh and a backing sheet, while applying a tanged tie strip to the exposed face of the sheet, pushing the tangs 5 through the sheet and the mesh, and bending the ends of the tangs against the exposed face of the mesh, during said advancing movement.

4. The method of applying a backing sheet to reinforcing mesh having ribs projecting from one 10 face thereof, which comprises imparting continuous traveling movement to the sheet and the mesh, in a direction transverse to the ribs, while holding the sheet against the ribs and deflecting it toward the plane of the mesh at points between 15 the ribs, and simultaneously applying tie strips in connected relationship with both the mesh and the sheet at said points.

5. The method of applying a backing sheet to reinforcing mesh having ribs projecting from one 20 face thereof, which comprises imparting continuous traveling movement to the sheet and the mesh, in a direction transverse to the ribs, while holding the sheet against the ribs and deflecting it toward the plane of the mesh at points 25 between the ribs, and simultaneously applying tie strips in connected relationship with both the mesh and the sheet at said points, the said strips extending in the same general direction of said movement.

30 6. The method of applying a backing sheet to reinforcing mesh having ribs projecting from one face thereof, which comprises imparting continuous traveling movement to the sheet and the mesh, in a direction transverse to the ribs, while 35 holding the sheet against the ribs and deflecting it toward the plane of the mesh at points between the ribs, and simultaneously applying tie strips in connected relationship with both the mesh and the sheet at said points, the said strips extending in the same general direction of said 40 movement, and being co-extensive in length with the mesh and the sheet.

ARCHWORTH MARTIN. 45
